UNITED STATES PATENT OFFICE.

WILLIAM A. LANGJAHR, OF PLYMOUTH, WISCONSIN.

BUGGY-IRON.

No. 874,774.

Specification of Letters Patent.

Patented Dec. 24, 1907.

Application filed August 22, 1907. Serial No. 389,625.

To all whom it may concern:

Be it known that I, WILLIAM A. LANGJAHR, a citizen of the United States, and resident of Plymouth, in the county of Sheboygan 5 and State of Wisconsin, have invented certain new and useful Improvements in Buggy-Irons; and I do hereby declare that the following is a full, clear, and exact description thereof.

10 The invention has for its main object to provide for the support of a swung back buggy-top from below the fulcrums of the jointed side braces of same, whereby good head-clearance is obtained without breaking 15 the jointed canopy braces to the detriment of said top.

A further object of the invention is to provide for supporting a swung back buggy-top as aforesaid or at the usual height at will, 20 and said invention consists in what is herein-after more particularly described with reference to the accompanying drawings and pointed out in the claims.

Figure 1 of the drawings illustrates a 25 swung back buggy-top, its shifting-rail and a reversible support for the top in accordance with my invention, parts being broken away and in section; Fig. 2, a perspective view of a fragment of the shifting-rail and the top- 30 support in connection therewith; Fig. 3, a front elevation of said rail and support partly broken away and in section, and Fig. 4, a horizontal section on the plane indicated by line 4—4 in Fig. 3.

35 Referring by letter to the drawings, A indicates a shifting-rail, B buggy-top bows connected to the rail in the usual manner, and C, D, jointed braces of the buggy-top. In connection with the shifting-rail is a de- 40 pending stationary angular yoke E and in slip-fit connection with the same is a reversi- 45 ble yoke F carrying a buffer G. The yoke E is provided with a horizontal upper outer stud constituting a fulcrum H upon which to secure the lower end of a jointed side-brace D of the buggy-top, the same construction occurring at both sides of the vehicle.

Each yoke F being in the position of the one herein shown, the buffer G therewith is a 50 predetermined distance below the shifting-rail in the path of the rear bow of the buggy-top when the latter is swung back, and the

support for this swung back top being thus lower than is ordinarily the case, good head-clearance is had without breaking its jointed 55 canopy braces, one of which is shown at C in Fig. 1.

Means attachable to a buggy, through the medium of a shifting-rail or otherwise, to provide for the support of the swung back top 60 of the vehicle below the fulcrums of the side braces of said top is within the scope of my invention, the showing herein being illustrative of a preferred form of said invention.

By reversal of the yoke F at each side of 65 the buggy from the position of the one herein shown, provision is had for supporting the swung back top of the vehicle at the customary elevation.

I claim:

1. A shifting-rail of a buggy having de- 70 pending rear supports for the swung back top of the vehicle below the fulcrums of the side-braces of said top.

2. A shifting-rail of a buggy having a 75 stationary depending rear yoke at each side, and a reversible yoke in slip-fit connection with the one aforesaid for the support of said top when swung back, the support being at one elevation or another according to the 80 arrangement of the reversible yokes.

3. A shifting-rail of a buggy having a 85 stationary depending rear yoke at each side, and a reversible buffer-carrying yoke in sliding fit connection with each stationary yoke for the support of the buggy-top when the same is swung back.

4. A shifting-rail of a buggy having a 90 stationary depending rear yoke at each side provided with an upper outer stud upon which to confine the lower end of a side-brace of the buggy-top, and a reversible buffer-carrying yoke in sliding-fit connection with each stationary yoke for the support of 95 said buggy-top when the same is swung back.

In testimony that I claim the foregoing I have hereunto set my hand at Plymouth, in the county of Sheboygan and State of Wisconsin in the presence of two witnesses.

WILLIAM A. LANGJAHR.
